UNITED STATES PATENT OFFICE.

AUGUSTUS W. DRAKE, OF LATTIMER MINES, PENNSYLVANIA.

SELF-OILING CAR-WHEEL.

SPECIFICATION forming part of Letters Patent No. 625,024, dated May 16, 1899.

Application filed June 25, 1897. Serial No. 642,288. (No model.)

To all whom it may concern:

Be it known that I, AUGUSTUS W. DRAKE, a citizen of the United States, residing at Lattimer Mines, in the county of Luzerne and 5 State of Pennsylvania, have invented a new and useful Self-Oiling Car-Wheel, of which the following is a specification.

As at present constructed the wheels of cars used in and around mines are fitted to the 10 axle spindles or journals to expose the latter. It is frequently the case that mining-cars become submerged in water owing to the flooding of the mine, and it has been found that the oil will be washed from the bearings and 15 the car rendered almost useless owing to the fact that the wheel is locked by a rust-joint to its spindle or journal, so that the car cannot be used until the wheels shall have been reoiled several times.

20 In my present invention the primary object is to construct an oiler for a mining-car wheel in a manner to effectually exclude the admission of water to the wheel-hub and axle-journal, and at the same time to provide for the 25 thorough lubrication of the protruding end of the axle-spindle.

According to my invention the hub of a mining-car is provided with means which tend to reinforce and strengthen the hub instead 30 of detracting from its strength, and the oiling and inclosing cap is of substantial construction and is united solidly and firmly to the car-wheel, so as to attain an exceedingly tight joint between the wheel-hub and the inclos- 35 ing cap.

A further object of this invention is to provide an improved oiling device which fits in close relation to the protruding end of the axle-spindle, so as to retain in position the 40 linchpin by which the wheel is prevented from displacement on the spindle, and this inclosing cap is of annular and substantial construction for the purpose of producing a smooth tread-surface to adapt the inclosing 45 cap for service as a guide-roller to travel upon a guide-rail usually provided adjacent to the car-tracks within a mine.

With these ends in view the invention consists in the novel construction and arrangement of parts which will be hereinafter fully 50 described and claimed.

In the drawings, Figure 1 is a side elevation

of the car-wheel constructed in accordance with my invention. Fig. 2 is a vertical trans- 55 verse section on the plane indicated by the line 2 2 of Fig. 1. Fig. 3 is a face view of the chambered cap, looking at the inside thereof.

Like numerals of reference denote like and corresponding parts in each of the several figures of the drawings.

1 designates the car-wheel, which is pro- 60 vided with an integral hub 2. In embodying my invention in a mining-car wheel it is not necessary to substantially alter or modify the construction of the wheel except to make pro- 65 vision for the attachment of the shouldered and flanged cap 5. This cap is applied to the car-wheel to inclose the protruding end of the wheel-spindle, and to provide for the rigid and solid attachment of the cap to the wheel- 70 hub the outer end of the hub 2 is provided with an annular continuous flange or face-plate 4. This flange or face-plate extends continuously around the end of the hub 2, so as to increase the strength and durability 75 thereof, and said flange is of circular form and preferably made as an integral part of the hub, as shown by Fig. 2.

The cap 5 is wrought or cast in a single 80 piece of metal; and it consists of an annu- lar wall 6, a head 7, and an offstanding an- 85 nular flange 8. The cap is of a diameter to fit across and over the open end of the hub 2, and the flange 8 of the cap is coincident with the flange or face-plate 4 of the wheel-hub, 90 thus providing two solid abutting faces on the wheel-hub and inclosing cap. The cap and wheel are united solidly together by a plurality of through-bolts 11, which are passed through coincident openings formed in the flanges 4 95 and 8 of the wheel-hub and the oil-cap, res- pectively, and between these abutting flanges 4 and 8 is interposed a gasket or packing 12, of rubber or any other suitable material. The gasket or packing is compressed between or 100 clamped firmly by the flanges and bolts, so as to secure an absolutely tight joint between the wheel-hub and the cap, and this gasket is wide enough to extend throughout the en- tire area of the abutting faces between the two flanges on the wheel-hub and cap, re- 105 spectively, so that the bolts 11 are caused to pass through the gasket as well as the coincident flanges. The interposition of the gas-

- ket between the cap and the flanged hub and the employment of the plurality of bolts which are arranged entirely around the hub and oiling-cap provides an improved joint which 5 serves effectually to exclude the admission of water to the outer end of the wheel-bearing, and in addition to excluding water from the hub the joint also obviates the leakage of the lubrication from the oiling-cap.
- 10 The axle journal or spindle 13 extends through the wheel-hub 2 into the chamber 10, which is formed by the cap 5 being bolted against the outer open end of the wheel-hub, and the wheel is held on its axle-spindle by 15 a linchpin 14, which passes through a suitable opening in the protruding end of the axle-spindle. The ends of this linchpin project beyond the cylindrical face of the protruding end of the axle-spindle, and as the cap is detachable from the wheel-hub it is obvious that 20 the linchpin may readily be inserted after the wheel has been slipped on the axle-spindle and before the cap is applied and bolted to the flange 4 of said wheel-hub. Provision is 25 thus made for readily assembling the parts together, so that the operator can observe the necessary conditions and spread the ends of the linchpin for holding it in engagement with the axle-spindle.
- 30 In my invention for use on a mining-car wheel it is necessary to make the cap 5 a solid substantial structure in order to resist the rough service to which the device is subjected when the mining-car is used in a mine, and 35 it is essential that the cap be bolted so firmly to the wheel-hub that it cannot be accidentally broken off when the car is thrown around and abused in its practical service. I therefore attach importance to the formation of the 40 cap in a solid heavy construction, to the employment of the abutting coincident flanges and bolts to form the exceedingly strong joint between the cap and wheel-hub, and to the formation of the cap with a circular plain unbroken surface adapted to serve as a tread and to permit the cap to ride upon a guide-rail, which is usually erected adjacent to a mining-car track within a mine. This substantial construction of cap with a circular 45 tread-surface enables the oiling-cap to ride freely upon a high guide-rail, and as the cap is of a solid, strong, and substantial construction and united firmly to the wheel-hub by the described means the cap is not liable to 50 be injured or broken when in use.
- 55 By reason of the construction referred to, whereby the cap 5 is enabled to travel or ride upon the guide-rail, provision is made for combining in a single structure both an oil-reservoir and a guide-roller for a mine-car. A structure of this character dispenses with the separate rollers or wheels which are usually fitted to mine-cars to travel upon the 60 guide-rails which are ordinarily used in connection with the tracks for mine-cars. It is well understood by those skilled in the art that mine-cars not only travel on the ordinary

tracks, but are also run on guide-rails, in order to elevate them for dumping their contents, and these guide-rails are disposed 70 at an inclination and lift the cars as they run forward. This operation is greatly facilitated by the cap 5 in the present invention, and the separate rollers or wheels are entirely dispensed with. Now the fact that 75 the cap 5 is utilized as a guide-roller necessitates the thorough reinforcing of the cap and its solid attachment to the wheel-hub. To accomplish this, the outer side wall or head of the cap is greatly strengthened by a 80 rounded annular reinforce-boss 17, which protrudes beyond the plane of the closure-plug 16 for the feed-port, so that this plug cannot become broken off by the cap striking an obstruction. In addition to the strengthening 85 action of the reinforcing-boss 17 an important feature to observe in the construction is the fact that the wheel-hub is provided at its outer end with the perfectly flat shoulder, which projects beyond the plane of the adjacent 90 side of the wheel and is adapted to have solidly bolted thereagainst the inner flanged end of the cap 5. The cap 5 is thus thoroughly braced to the wheel and lies wholly outside of the plane of the adjacent side of 95 the wheel, so that no projecting part of the wheel interferes with the function of the cap as a supplemental guide-roller for a mine-car.

In the center of the head 7 is provided a feed-port 15, through which the lubricant may 100 be introduced from time to time into the chamber of the cap, thus obviating the necessity for removing the cap when it is desired to renew the supply of lubricant to the chamber of the oiling device. This feed-port 105 is interiorly screw-threaded to receive a closure-plug 16, which is also threaded and is screwed into the port 15, said plug serving as a medium for closing the central port in the cap against ingress of water or the leakage of 110 the lubricant. To protect the plug from being broken should the car-wheel cap strike an obstruction, the head 7 of said cap is formed with an integral boss or rib 17, which projects beyond the face of the cap and 115 encloses the plug 16, so as to serve as a guard or shield therefor.

The chambered cap 5 is provided on the inner surface of its annular wall 7 with a series 120 of grooves or channels 18, which are arranged in planes parallel to the axis of the cap and open inwardly to communicate with the chamber 10 within the oiling device. These grooves form a series of pockets or receptacles in 125 which the lubricant may accumulate and by which it is carried upwardly as the wheel and cap are rotated, so as to discharge the lubricant upon the protruding end of the axle-spindle, from whence the lubricant finds its way into the wheel-hub 2.

The flange 8 is at the end of the chambered cap, so as to entirely expose the annular tread-surface of the cap, and this flange registers or coincides exactly with the flange 4 of the

wheel-hub. The two flanges 4 and 8 are continuous around the wheel-hub and the inner end of the cap, and this shape of the flanges provides for the employment of a greater number of bolts than can be used in connection with any other style of flanges.

Cars fitted with wheels embodying my invention have been covered with water in flooded mines for a period of forty-eight hours, 10 and when the water was pumped from the mine the cars moved off as easily as if they had not been standing in water. This is a very important feature around mines, as they are flooded many times during a year. With 15 ordinary cars the wheels become rusted on their axle-spindles, and it is almost impossible to move the cars on the track, which results in considerable delay, annoyance, and expense. These objections are entirely overcome by my invention, which effectually excludes the admission of water and also prevents dirt and grit from working into the parts to wear the same.

The annular lubricating-cap is proportioned 25 to fit snugly to the protruding end of the axle, so that it lies close thereto, and this cap serves to hold the linchpin 14 from displacement in the end of the axle-spindle. The diameter of the cap is such that it fits in close relation 30 to the axle-spindle and the linchpin, so that the ends of the linchpin will clear the grooved face of the cap, and thus the parts are disposed to attain the desired operation, while preventing disengagement of the linchpin.

Having thus described the invention, what 35 I claim is—

1. In a mining-car wheel, the combination of the wheel-hub provided at its outer end with a flat shoulder projected beyond the 40 plane of the adjacent side of the wheel, and a continuous exterior flange 4, surrounding the peripheral edge of the shoulder flush with the latter, a combined oil and roller cap having its inner end abutting flat against said 45 shoulder and provided thereat with an exterior continuous flange registering with the

flange 4 of the wheel-hub, said cap lying wholly outside of the plane of the adjacent side of the wheel and provided beyond its flange with a widened truly cylindrical and horizontal exterior tread-surface for travel upon a guide-rail, and also provided centrally in its outer side wall with a plug-closed feed-port and with an exterior rounded protective boss surrounding the port and protruding beyond the plane of the closure thereof, a gasket completely filling the space between the contacting flanges, and a plurality of bolts connecting the flanges and compressing the gasket to form a liquid-tight joint, substantially as set forth. 50

2. In a mining-car, the combination of the wheel-hub provided at its outer end with a flat shoulder, and a continuous exterior flange surrounding the peripheral edge of the shoulder flush with the latter, the axle-spindle having its terminal projecting beyond the flat shoulder at the outer end of the wheel-hub, and a cylindrical oil-cap bolted at its open side solidly against the flat shoulder at the 65 outer end of the wheel-hub and forming a liquid-tight joint therewith, said cap completely housing the contiguous protruding end of the axle-spindle and provided in the inner surface of its annular wall with a plurality of short grooves or channels opening 70 inwardly to communicate with the interior of the cap, and arranged in planes parallel, and of a length equal, to the length of the protruding end of the axle-spindle, whereby 75 the lubricant is elevated by the grooves or channels and deposited upon the protruding end of the axle-spindle from whence it works into the adjacent wheel-hub, substantially as set forth. 80

In testimony that I claim the foregoing as my own I have hereto affixed my signature in the presence of two witnesses.

AUGUSTUS W. DRAKE.
